Godfrey Staiger,
By Almon H. Hall, Atty.

UNITED STATES PATENT OFFICE.

GODFREY STAIGER, OF TOLEDO, OHIO.

BUNG AND BUNG-BUSHING.

SPECIFICATION forming part of Letters Patent No. 663,049, dated December 4, 1900.

Application filed April 23, 1900. Serial No. 13,860. (No model.)

To all whom it may concern:

Be it known that I, GODFREY STAIGER, a citizen of the United States, residing at Toledo, in the county of Lucas and State of Ohio, have 5 invented certain new and useful Improvements in Bungs and Bung-Bushings; and I do declare the following to be a full, clear, and exact description of the invention, such as will enable others skilled in the art to which 10 it appertains to make and use the same, reference being had to the accompanying drawings, and to the figures of reference marked thereon, which form a part of this specification.

My invention relates to bungs and bushings therefor for barrels and casks such as are used for ale, beer, and the like, and more particularly to that class of bung-bushings consisting of two rings screw-threaded to engage each other and having flanges to clasp between them the margin of the bung-hole.

The object of my invention is to provide a bung and bung-bushing in which the two flanged rings may be engaged with each other and caused to clamp the margin of the bung-hole and in which the parts may be assembled and secured in position without disturbing a stave and without removing a head from the cask or barrel. I attain this object by means of the devices and arrangement of parts hereinafter described, and shown and illustrated in the accompanying drawings, in which—

Figure 1 is a central transverse sectional view of my device, taken longitudinally of the stave. Fig. 2 shows the stave and bung partly in section, with the inner ring half-way through the bung-hole, illustrating the manner of introducing the inner ring into the interior of the cask; and Fig. 3 is a plan view of the bung-hole seen from the inner side of 40 the stave with the rings removed.

Like numerals of reference indicate like parts throughout the drawings.

In the drawings, 1 is the outer bushing-ring, provided with a flange 2 of sufficient 45 width to overlap the margin of the bung-hole outside the stave. This ring is screw-threaded exteriorly, as at 3, and is provided with a tapered shoulder 4, disposed in the angle of the flange and the body of the ring.

50 5 is the inner ring, interiorly screw-threaded to take the threaded portion of the ring 1. This ring is provided with a flange 6 to overlap

the margin of the bung-hole inside the stave. At opposite sides of the ring the flange 6 is cut away, as at 7, on parallel lines, as shown 55 in Fig. 2. The removal of the two segments leaves the diameter of the inner ring such that the ring will barely pass through the bung-hole in the direction of the straight lines of the mutilated portions of the flange. Upon 60 the side of the flanges 6 next the wood are formed sharp spurs 8. The margin of the bung-hole at opposite sides is beveled or chamfered inside the stave, as at 9, (see Fig. 3,) to correspond with the contour of the faces 65 of the mutilated flange 6. This shaping of the wood may be readily accomplished from outside the bung-hole by means of a sharp curved knife. The inner ring is slipped edge-wise through the bung-hole, with the two parallel sides 7 adjacent to the sides of the bung-hole and the ring is then turned so that the threaded body of the ring slips into the opening. The ring is now supported in this position by means of a two-pronged hook or other 70 suitable instrument, while the outer ring is screwed into the inner ring. As soon as the threads of the two rings are engaged the hook or other instrument may be removed. The outer and inner rings are now drawn powerfully together by means of an expansion-wrench, causing the spurs 8 to sink into the wood on the inner side of the stave, which prevents the inner ring from turning during the operation of screwing the two parts together. 85 As the outer ring is screwed home the tapered shoulder 4, by the wedge-like action of a truncated cone, completely fills the opening at its outer margin, and at this point the shoulder now fits so closely that the wood is compressed 90 and the cask is securely sealed against escape of liquid or gas between the outer margin of the bung-hole and the ring 1.

Having described my invention, what I claim, and desire to secure by Letters Patent, 95 is—

1. A bung-bushing comprising a pair of screw-threaded rings adapted to engage each other, flanges on said rings adapted to clamp between them the margin of the bung-hole, 100 mutilated flange portions at opposite sides of the inner ring, whereby the inner ring may be passed through the bung-hole, spurs on the flange of the inner ring adapted to engage the

inner side of a stave, and a tapered portion upon the outer ring in the angle of the flange and ring.

2. In a bung and bung-bushing, a stave having a circular aperture therethrough, beveled or chamfered margins for said opening on opposite sides thereof on the inner side of the stave, a bushing-ring of approximately the same diameter as the opening, a flange for said bushing-ring having portions cut away at opposite sides of the ring, whereby the ring may be passed edgewise through the open-

ing, the remaining portions of the ring conforming to said chamfered portions of the margin of the opening, an outer flanged ring, ¹⁵ and means for engaging said rings together and for clamping the margin of the opening between the flanges of said two rings.

In testimony whereof I affix my signature in presence of two witnesses.

GODFREY STAIGER.
